CLAIM

The ornamental design for a sample storage tube, as shown and described.

DESCRIPTION

FIG. 1 is a perspective view of a sample storage tube. FIG. 2 is a front view of the sample storage tube depicted in FIG. 1, with the rear view being identical.

FIG. 3 is a left side view of the sample storage tube depicted in FIG. 1, with the right side view being identical; and, FIG. 4 is a bottom view of the sample storage tube depicted in FIG. 1.

In the drawings, the broken lines depict portions of a sample storage tube that form no part of the claimed design.
